H. HARTMAN.
TOILET POWDER DISPENSER.
APPLICATION FILED NOV. 22, 1917.

Patented July 29, 1919.

UNITED STATES PATENT OFFICE.

HANS HARTMAN, OF NEW YORK, N. Y.

TOILET-POWDER DISPENSER.

1,311,227.

Specification of Letters Patent. Patented July 29, 1919.

Application filed November 22, 1917. Serial No. 203,359.

To all whom it may concern:

Be it known that I, HANS HARTMAN, a subject of the Emperor of Austria-Hungary, and resident of New York city, in 5 the county of New York and State of New York, have invented certain new and useful Improvements in Toilet-Powder Dispensers, of which the following is a specification.

This invention contemplates an improved 10 dispenser for dispensing toilet powders of various kinds and particularly powder soap.

Known devices for the same or a similar purpose have often the disadvantage that the powder, especially powder soap, tends 15 to clog and choke the delivery openings which must naturally be of very limited size or that in some other way the proper function of the delivery mechanism is impaired.

The main object of the present invention 20 is therefore to overcome such difficulties by forcing the powder mechanically through the delivery openings and not merely to allow its passage by gravity or vibration.

Another object of the invention is to provide 25 a device of this kind of very simple construction, therefore cheap to manufacture and not liable to get out of order and which is at the same time of solid and neat appearance.

In this specification and annexed drawings I illustrate the invention in the form 30 which I consider the best, but it is to be understood that I do not limit myself to such particular form because the said invention 35 may be embodied in other forms. I am therefore showing also a modification of my invention in another form and it is to be understood that in and by the claims following the description herein, I desire to 40 cover the invention in whatever form it may be embodied.

The invention consists in certain novel 45 features of construction and combination and arrangement of parts as will be more fully hereinafter described and pointed out in the appended claim.

In the accompanying drawings:

Figure 1 is a side view of a device embodying my invention in section and with 50 parts in elevation.

Fig. 2 is a vertical front elevation of the same.

Fig. 3 is a plan view of the device.

Fig. 4 is a transverse section taken on 55 line A—A of Fig. 1.

Fig. 5 is a front view partly in section

and partly in elevation, showing a modified form of my invention.

Referring to the different views, similar reference letters designate similar parts. 60

The dispenser comprises a receptacle or body 1, having a removable top portion or cover 2, and a bracket 3, for attaching the device to a wall or the like. Within the body 1, is arranged a shaft 4, carrying a 65 spiral screw or conveyer 5, which is journaled with one end in the center of the bottom 6 of said body 1 as shown at 7 whereby a portion 7, slightly reduced in diameter passes said bottom 6 being formed into a 70 rivethead outside as indicated at 9.

Near its upper end shaft 4 is guided through a bracket or arm 10, as shown at 11, said bracket or arm 10 being attached to the inner wall of receptacle 1, by medium of 75 rivets 12. The portion of shaft 4 above bracket 10 is of square shape as shown at 13, so as to fit freely into a corresponding square hole 14 provided in the lower end of a second shorter shaft 15, which is leading 80 through a hole in cover 2 with reduced diameter and having outside a knob 16, which is riveted tight onto shaft 15. A curved arm 5^a extends horizontally from shaft 4 above the spiral 5, agitating the contents of 85 casing 1 when shaft 4 is rotated.

While the cover 2 engages at one side an inner projection of body 1 as shown at 17, it can be locked opposite such projection by medium of a screw 18, passing through the 90 wall of body 1 and a part of cover 2 as shown at 19.

The bottom 6 of body 1 is provided with delivery holes or openings 20. Bracket 3 terminates in a suitable base 21, having holes 95 22 for attaching the device to a wall, et cetera. The receptacle or body 1 is of conical shape at its lower end as shown at 23, having a cylindrical extension 24 within which a portion of the spiral screw or conveyer 5 100 is seated.

In the modified form as shown in Fig. 3 the cylindrical extension 24 is arranged horizontally and therefore also the shaft 4 carrying the spiral screw conveyer 5 is located in said cylindrical extension in a horizontal position and projecting with one end therefrom having the knob 16 attached directly to its outer end. In this modification the part 6 through which the other end of shaft 4 passes is removably attached to the cylindrical extension by medium of screws 105 110

25, having otherwise the same delivery openings 20 as described above.

The *modus operandi* of my dispenser may be stated as follows:

5 Assuming the device to be attached in its normal operative position to a wall or the like by medium of the bracket 3, the cover 2 can be readily removed by turning screw 18 so far out that its inner end passes out 10 of cover 2 and then by turning said cover slightly until the same disengages with its opposite slotted part the inner projection of the wall of body 1 as shown at 17. The cover can then be lifted from body 1 and 15 the latter filled with toilet powder, powder soap or the like. When the cover is replaced in the same, but reverse manner, care has to be taken that the square hole 14 in shaft 15 engages properly the square shaped 20 upper end 13 of shaft 4. It can be seen from the drawing that the cover 2 cannot assume its proper position if this is not the case, as it would otherwise rest with the lower end of shaft 15 on top of shaft 4.

25 After the cover 2 has been properly replaced and screw 18 turned again into engagement with the corresponding part of cover 2, the dispenser is ready for delivery and will deliver its contents in small quantities through the holes 20 provided for this 30 purpose in bottom 6 as soon as knob 16 is turned in the right direction. This will cause shaft 4, which is then connected through its square seat in shaft 15, and also 35 the spiral screw conveyer 5 to rotate and to convey some of the powder contained in the receptacle 1 through the cylindrical extension 24 and as there is no other way for such powder to escape the resulting pressure 40 upon its arrival at the bottom 6, it will be forced through the openings 20.

In the modified form as shown in Fig. 3, the powder will fall by gravity into the spiral screw conveyer 5 and the turning of 45 knob 16 in the proper direction will force it sidewise through the openings 20 in the

bottom cover 6. In this modified form said bottom cover 6 had to be removably arranged so as to permit the insertion of shaft 4 and spiral screw 5. But otherwise the 50 principle of such modified form of my dispenser is exactly the same as described in this specification. The curved arm 5^a, extending from shaft 4 above the upper end of the spiral conveyer 5 will agitate the contents of the device when shaft 4 is rotated, and tend to throw powder toward the center of the casing 1 respectively against the spiral conveyer on account of its curvature. 55

The delivery end of conveyer 5, as shown, 60 bears against cover 6 and passes over the holes 20 as the conveyer rotates. The powder contents of body 1 is not only forced by the spiral conveyer against cover 6, but is pushed through the holes 20 by the end 65 of the conveyer as it sweeps along cover 6.

I claim:

In a dispensing device of the character described, the combination of a receptacle having means whereby said receptacle can 70 be attached to a support, a cylindrical extension at one end of the receptacle closed by a perforated plate, a removable cover at the opposite end of the receptacle, a spiral conveyer within the receptacle operative 75 within the said extension and having a shaft journaled at one end within said perforated plate and its other end operatively engaged by means on said cover for rotating the shaft when the cover is in operative position, and an agitator connected with said shaft above the conveyer within the receptacle to agitate its content during rotative operation of the conveyer. 80

Signed at New York, in the county of 85 New York and State of New York, this twenty-first day of November, A. D. 1917.

HANS HARTMAN.
